UNITED STATES PATENT OFFICE

JOHN OLIPHANT, OF CHICAGO, ILLINOIS, ASSIGNOR TO SULLIVAN MACHINERY COMPANY, A CORPORATION OF MASSACHUSETTS.

DISPLACEMENT PUMPING SYSTEM

Application filed April 18, 1927. Serial No. 184,785.

This invention relates to displacement pumping systems and more particularly to controlling arrangements for such pumping systems.

An object of the invention is to provide an improved displacement pumping system. Another object of the invention is to provide an improved displacement pumping system having improved controlling mechanism. A further object of the invention is to provide an improved controlling mechanism for displacement pumping systems in which liquid level variation in the displacement tanks may effect control of the pumping fluid supply and discharge relative to the tanks through improved mechanism. A still further object of the invention is to provide an improved controlling mechanism for a displacement pumping system in which the liquid level in the tanks may control through pilot means the shifting of the main pumping fluid controlling valves. Other objects and advantages of the invention will subsequently appear.

In the accompanying drawings I have shown for purposes of illustration one form which my invention may assume in practice.

In these drawings,—

Fig. 1 is a plan view of a displacement pumping system in which the illustrative embodiment of the invention is incorporated.

Fig. 2 is a side elevation with parts broken away of the mechanism of Fig. 1.

Fig. 3 is an enlarged vertical section on the line 3—3 of Fig. 1.

Fig. 4 is an enlarged vertical section on the line 4—4 of Fig. 1.

Referring to the drawings, 1 represents a displacement pumping unit comprising a plurality of alternately filling and discharging tanks respectively designated 2 and 3. Each of the tanks is provided with liquid supply and discharge means in the form of a central connection 4 having branches 5 and 6 which are respectively controlled by a discharge check valve 7 and an intake check valve 8. This connection is shown as being at the bottom of the tank although it will be understood that it may be made at any desired point, as for example, at the top of the tank in which

instance a pipe might be employed inside and extending toward the bottom of the tank. Pumping fluid is supplied to the tanks under the control of mechanism later to be described from a receiver 9 to which fluid is supplied by a compressor 10 through a pipe 11, and to facilitate filling of the tanks the filling tanks are connected with the intake side of the compressor through a line 12. It will be understood that a plurality of these pumping units may be used and operated by the same compressor and where more than a single unit is employed the lines 11 and 12 may be extended as indicated in Fig. 1. The admission of pumping fluid and the filling of the tanks 2 and 3 is controlled by a common valve mechanism, generally designated 15, which comprises a casing 16 provided with a valve seat 17 upon which a slide valve 18 is reciprocable. The seat 17 is traversed by ports 19, 20, 21 and 22 and the slide valve controls communication between the port 19 and the ports 20 and 22 by means of its outside edges 23 and 24 respectively, while communication between the ports 20 and 22 and the port 21 is controlled by a usual recess 25. A bypass passage 26 is also formed in the valve to interconnect the ports 20 and 22 when the valve is in mid-position. The port 19 communicates with the main air line 11 through a pipe 27. The port 20 communicates with the tank 3 through connections later more fully described, but including a pipe 28. The port 21 communicates through a pipe 29 with the suction line 12, and port 22, through connections including a pipe 30, is communicable with the tank 2.

Operation of the valve 18 is controlled by means of a servo-motor 32 comprising a cylinder 33 in which a piston 34 is reciprocable. The piston 34 is connected by a rod 35 with the valve 18 and transmits motion in opposite directions to the latter on its own opposite movements. The movements of the piston 34 are controlled by variations in the pressures at the opposite sides thereof and the supplies of fluid to the opposite ends of the piston 34 are respectively controlled by mechanisms associated with the tanks 2 and 3. Herein the pressure conditions at the end 100

of the cylinder 33 remote from the valve chest 16 are controlled by mechanism associated with the tank 2, while pressure conditions at the opposite side of the piston 34 are controlled by conditions in the tank 3. The cylinder 33 has a central exhaust port 36 which is uncovered as the piston 34 approaches the opposite ends of its path of movement and means for preventing excessive pressures at the ends of the cylinder as the piston approaches the latter are also provided, the same constituted herein by pinhole vents 36'.

Referring to Fig. 2, it will be observed that a suitable stop valve controlled line 37 communicates through a pressure reducing valve 38 with a branched connection 39 whose separate branches 40 and 41 lead respectively into juxtaposition to the tanks 2 and 3. Since the mechanism now to be described is substantially identical in the case of both tanks, that associated with the tank 3 will alone be described.

Referring particularly to Fig. 4, it will be noted that upon the top of tank 3 is mounted a casing 43 in free communication with the interior of the tank. A ball float 44 is guided for vertical movement in the chamber 43 by a stem 44^a, which at its lower end is movable in a bore 44^b in a transverse bearing member 44^c which prevents the float 44 from falling out of the chamber 43 into the tank. At the upper side of the ball 44, the stem is threaded into a suitably guided valve member 45, later more fully described, the latter being provided with a guided operating stem 46, whereby the ball is adequately guided both at top and bottom. The valve 45 is provided with a seat-engaging, ring-like washer member 46^a which is adapted to cooperate with a seat 47^a surrounding a passage 48 connecting with the pipe 28. Accordingly on upward movement of the float 44, the packing 46^a will engage the seat 47^a and close communication between the chamber 43 and the pipe 28. This mechanism is a safety arrangement and has as its function precluding the possible entry of the liquid to be pumped, into the line 28. The passage 48 is formed in a cap member 49 which at its upper end supports a pilot valve housing 50. The latter contains a seat 51 for a ball valve 52 which is normally maintained seated by a spring 53, but which may be opened through engagement by the stem 46 on upward movement of the float 44. It will be noted that the stem 46 is of sufficient length to engage the valve 52 before the valve 45 engages its seat. The connection 41 communicates with the space above the valve 52 on the top of tank 3, while the connection 40 communicates with the similar connection at the top of tank 2. From below the seats of the ball valves 52 connections lead to the opposite ends of cylinder 33, the valve 52 associated with tank 3 controlling supply to such a connection 55 leading to the end of cylinder

33 nearer the valve mechanism 15, while the valve 52 associated with the tank 2 controls supply to a connection 56 leading to the other end of cylinder 33.

It is believed that the mode of operation of the mechanism heretofore described will already be obvious, but a cycle of operations may be set forth. Let it be assumed that liquid under appropriate head or even from a level within the limits of lifting action of the suction of the compressor 10, has flowed into tank 2, filled the latter, and raised the float 44 in chamber 43 on top of tank 2. Then valve 52 controlling connection 56 will be unseated by its rod 46 and pressure fluid will flow through line 37, reducing valve 38, line 40 and connection 56 to the right hand end of the cylinder 33 as viewed in Fig. 3. The piston is shown, in the figure mentioned, moving from right to left, and obviously, with the tank 3 discharging, the gaseous pumping fluid therein would be transmitted through line 28, port 20, passage 26, port 22 and passage 30 to fill the latter line and begin the discharging of liquid from tank 2. The piston 34, continuing its movement to the left, would finally open the exhaust port 36 and in that position would have moved valve 18 to uncover port 22 and connect ports 20 and 21. The left leak port 36' would permit ready movement of piston 34 as described. In left hand extreme position of piston 34 and valve 18, gaseous pumping fluid at full receiver pressure will flow through pipe 27, port 19, port 22, and pipe 30 to discharge the liquid from tank 2, and tank 3 will be connected through pipe 28, port 20, recess 25, port 21 and pipe 29 with the compressor intake so as to facilitate filling of tank 3. As soon as the liquid level in the chamber 43 at the top of tank 2 is lowered sufficiently to permit the float to drop and release the valve 52, no more air will be supplied through line 56 and the pressure in the right hand end of cylinder 33 would drop to atmospheric. The time required for shifting the valves is relatively short so that it will be moved to its extreme position before the liquid level in the chamber 43 is lowered sufficiently to cause the float 44 to drop enough to permit closing of the valve 52. The valve 18 and piston 34, being substantially balanced, would remain in left hand position (Fig. 3), the friction on the packings offsetting the slight unbalanced pressure on valve 18. Now, it will be evident that when tank 3 is completely filled raising its float 44, the piston 34 and valve 18 will be moved to the right and the tank 3 emptied while tank 2 is filling.

From the foregoing description, it will be obvious that there is provided an improved and advantageous displacement pumping mechanism in which means is provided whereby the liquid levels in the filling tanks control the admission of pumping fluid there-

to while all risk of liquid entrance to the gaseous pumping fluid lines is prevented, in which pumping fluid is conserved, in which each element of a unit-pair performs a controlling function for the others as well as one for itself, and in which a simple arrangement of parts and low operating pressures for the controlling devices are made possible.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a displacement pump, a displacement tank, pumping fluid supply means therefor including means forming a connection opening through the top of the tank, controlling means for said pumping fluid supply means including a main pressure fluid actuated valve, a pilot valve mounted on said tank in alignment with said connection for controlling flow of pressure fluid to actuate said main valve and a float in said tank for controlling said pilot valve, and means controlled by said float to prevent liquid entering said connection.

2. In a displacement pumping apparatus, a pair of displacement tanks, common valve mechanism for controlling supply of pumping fluid to and venting of pumping fluid from said tanks and for interconnecting the latter, and means associated with each of said tanks and controlled by the level of liquid therein for controlling moving of said valve mechanism in one direction.

3. In a displacement pumping apparatus, a pair of displacement tanks, common valve mechanism for controlling supply of pumping fluid to and venting of pumping fluid from said tanks, a piston for actuating said valve mechanism, a cylinder in which said piston is reciprocable, and means for admitting fluid to one end of said cylinder associated with one of said tanks and for admitting fluid to the other end of said cylinder associated with the other of said tanks, said cylinder having a piston controlled exhaust midway between its ends, and other means for further exhausting said cylinder.

4. In a displacement pumping apparatus, a pair of displacement tanks, common valve mechanism for controlling supply of pumping fluid to and venting of pumping fluid from said tanks, a piston for actuating said valve mechanism, a cylinder in which said piston is reciprocable, and means for admitting fluid to one end of said cylinder associated with one of said tanks and for admitting fluid to the other end of said cylinder associated with the other of said tanks, said

cylinder having a piston controlled exhaust midway between its ends and having also means for limiting pressures built up by movement of said piston into either end thereof.

5. In a displacement pumping apparatus, a pair of displacement tanks, common valve mechanism for controlling supply of pumping fluid to and venting of pumping fluid from said tanks, a piston for actuating said valve mechanism, a cylinder in which said piston is reciprocable, and means for admitting fluid to one end of said cylinder associated with one of said tanks and for admitting fluid to the other end of said cylinder associated with the other of said tanks, said cylinder having a piston controlled exhaust midway between its ends, said cylinder having vent ports of small area formed in each end thereof for limiting pressures built up by movement of said piston.

6. In combination, a displacement tank having an open top, a float chamber mounted on said top and overlying and communicating with said opening, a float in said float chamber, a pumping fluid supply connection mounted in and opening into the top of said float chamber, a valve seat surrounding the mouth of the supply connection, a valve movable with said float and adapted to seat on said valve seat, a fluid pressure actuated valve for controlling supply and exhaust of fluid through said connection, and a pilot valve mechanism for controlling flow of pressure fluid to said first mentioned valve, said mechanism being supported on said fluid supply connection and controlled by said float.

7. In a displacement pumping apparatus, a pair of displacement tanks, valve mechanism for controlling supply of pumping fluid to and venting of pumping fluid from said tanks, pressure fluid actuated means for operating said valve mechanism, a pilot valve on one of the tanks for controlling flow of fluid to said operating means to cause movement of said valve mechanism to effect flow of pumping fluid for causing functioning of said tanks in one manner, and a pilot valve on the other of said tanks for controlling flow of fluid to said operating means to cause movement of said valve mechanism to effect flow of pumping fluid for causing functioning of said tanks in another manner, a float in each of said tanks for automatically operating said pilot valves, and a valve carried by each of said floats for controlling discharge of liquid from the respective tank.

8. In a displacement pump, a displacement tank, pumping fluid supply means therefor including means forming a connection opening into the tank, controlling means for said pumping fluid supply means including a main pressure fluid actuated valve, a pilot valve for controlling flow of pressure fluid to actuate said main valve, and a float in said
